US00D928946S

(12) **United States Design Patent** (10) Patent No.: **US D928,946 S**
(45) Date of Patent: **** Aug. 24, 2021**

(54) URINE RECEIVING APPARATUS	3,087,938 A	4/1963	Hans et al.
(71) Applicant: PUREWICK CORPORATION , El Cajon, CA (US)	3,198,994 A	8/1965	Hildebrandt et al.
(72) Inventors: Robert A. Sanchez , Riverton, UT (US); Camille R. Newton , Bonsall, CA (US); Joseph M. Forehand , La Mesa, CA (US); Raymond J. Newton , Bonsall, CA (US)	3,312,981 A	4/1967	McGuire et al.

CLAIM

The ornamental design for a urine receiving apparatus, as shown and described.

DESCRIPTION

FIG. 1 is a perspective view of a urine receiving device in a first configuration, according to a new design;

FIG. 2 is a side elevational view of the urine receiving device shown in FIG. 1, with the other side elevational view being a mirror image;

FIG. 3 is a top plan view of the urine receiving device shown in FIG. 1;

FIG. 4 is a bottom plan view of the urine receiving device shown in FIG. 1;

FIG. 5 is a rear elevational view of the urine receiving device shown in FIG. 1;

FIG. 6 is a front elevational view of the urine receiving device shown in FIG. 1;

FIG. 7 is a perspective view of the urine receiving device shown in FIG. 1 in a second configuration, during use;

FIG. 8 is a side elevational view of the urine receiving device shown in FIG. 7, with the other side elevational view being a mirror image;

FIG. 9 is a top plan view of the urine receiving device shown in FIG. 7;

FIG. 10 is a bottom plan view of the urine receiving device shown in FIG. 7;

FIG. 11 is a rear elevational view of the urine receiving device shown in FIG. 7; and,

FIG. 12 is a front elevational view of the urine receiving device shown in FIG. 7.

The broken line showing of parts of the drawings is included for the purpose of illustrating use and environment and forms no part of the claimed design.
